RAILWAY SIGNALING

Filed Feb. 16, 1929

UNITED STATES PATENT OFFICE

CHARLES W. BELL, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SIGNALING

Application filed February 16, 1929. Serial No. 340,453.

My invention relates to railway signaling, and particularly to means for selecting the controls for railway signals according to the direction of traffic movements over the 5 stretch of track with which such signals are associated.

One feature of my invention is the provision of means for reducing the number of line wires necessary for the directional control of railway signals.

I will describe one form of apparatus embodying my invention, and will then point out the novel features thereof in claims.

The accompanying drawing is a diagrammatic view showing one form of apparatus embodying my invention.

Referring to the drawing, reference character Y designates a stretch of railway track with which a passing siding Z is connected by manually operable switches F¹ and F². Rails 1 and 1^a of stretch Y are divided by means of insulated joints 2 into sections A—B, B—C and C—D. Each of these sections is provided with a track circuit which 20 is supplied with current by a battery 3 connected across the rails adjacent one end of the section, and which includes a relay designated by the reference character G with a distinguishing suffix and connected across 25 the rails adjacent the opposite end of the section.

Two signals each of which is designated by the letter S with a distinguishing suffix, are located on opposite sides of the track adjacent 30 each pair of insulated joints 2 at points A, B, C and D. As here shown, these signals are of the semaphore type and are capable of displaying any one of three indications, namely, "high speed", "reduced speed", and 35 "stop". The high speed and reduced speed indications will hereinafter be referred to as the "proceed" and "caution" indications, respectively. Signals S¹, S³, S⁵ and S⁷ govern westbound traffic, that is, traffic moving toward the left as shown in the drawing, and signals S², S⁴, S⁶ and S⁸ govern eastbound traffic, that is, traffic moving toward the right as shown in the drawing.

My invention is completely illustrated by 40 the control circuits as shown for signals S⁵

and S⁷. Signals S⁴ and S² may be controlled similarly, respectively, to signals S⁵ and S⁷. Signals S¹, S³, S⁶ and S⁸ may be controlled, similarly to corresponding signals in a well known system of signaling which is called 55 "absolute permissive block signaling".

Polarized line relays, designated by the reference character H with a distinguishing suffix, are shown for signals S³, S⁵ and S⁷, but the complete circuits for such relays are 60 shown only in connection with signals S⁵ and S⁷. The control for relay H³ may be similar to that which is provided for a similar relay controlling a corresponding signal in absolute permissive block signaling. A slow release relay P is controlled by a front contact 65 of relay H³.

A stick relay T is arranged to become energized when a westbound train passes signal S³, and to continue energized while the train 70 is proceeding through section A—B.

Relay H⁵ is operated by direct current of normal or reverse polarity supplied to line wires 19 and 25 by a battery Q¹. Transformer M is energized by alternating current 75 supplied to the same wires 19 and 25 by an alternating current source X. Impedance units 16 and 20, having a high impedance to alternating current but low resistance to direct current, obstruct the flow of alternating 80 current from source X through battery Q¹ and the winding of relay H⁵, respectively. Resistance units 76 and 22 obstruct the flow of direct current from battery Q¹ through source X and the primary winding 23 of 85 transformer M, respectively.

The secondary winding 28 of transformer M supplies alternating current to a rectifier R which in turn supplies direct current to the winding of relay N. As here shown, rectifier R comprises asymmetric units 29, 30, 31 and 32, each of which may be similar to those disclosed and claimed in Letters Patent of the United States, No. 1,640,335, granted to L. O. Grondahl, August 23, 1927. 90

Having thus described, in general, the arrangement and location of the various parts comprising my invention, I will now describe the operation of the apparatus.

As shown in the drawing, all parts are in 100

their normal condition, that is, track sections A—B, B—C and C—D are unoccupied, switches F¹ and F² are set in their normal position which is the position for directing traffic along stretch Y only and not to or from siding Z, and all signals are indicating "proceed". Signal S³ is indicating proceed because relay H³ is energized in its normal direction by a circuit, shown in part, through contact 4 of relay G¹. The circuit for operating signal S³ to its proceed position passes from battery Q¹, through wires 5, 10, 45 and 46, contact 47 of relay P, wire 48, contact 49^a of relay H³, wire 50, operating mechanism of signal S³, and wire 52 back to battery Q¹.

With relay H³ energized, relay P is energized by its circuit passing from battery Q¹, through wires 5 and 6, contact 7 of relay H³, wire 8, winding of relay P, and wire 9 back to battery Q¹. With relay P energized and relays G¹ and G² energized, current of normal polarity is supplied for energizing relay H⁵ by a circuit passing from battery Q¹, through wires 5 and 10, contact 11^a of relay P, contact 12 of relay G¹, impedance unit 16, wire 17, contact 18 of relay G², wire 19, impedance unit 20, winding of relay H⁵, wires 21, 25 and 26, contact 27^a of relay P, and wire 9 back to battery Q¹. With relays P and G² energized, alternating current is supplied to the primary 23 of transformer M by a circuit passing from source X, through wire α , contact 74 of relay P, wire 75, resistance unit 76, wire 17, contact 18 of relay G², wire 19, resistance unit 22, primary winding 23, wires 24, 25 and 78, contact 77 of relay P, and wire α back to source X.

With alternating current flowing through primary winding 23, secondary winding 28 of transformer M is supplying alternating current to rectifier R which in turn supplies direct current for energizing relay N by a circuit passing from rectifier R, through wire 33, contact 34 of relay H⁵, wire 35, winding of relay N, and wire 36 back to rectifier R. With relay N thus energized and with relay G³ energized, current of normal polarity is supplied for energizing relay H⁷ by its circuit passing from a battery Q², through wire 37, contact 38^a of relay N, wire 39, contact 40 of relay G³, wire 41, winding of relay H⁷, wire 42, contact 43^a of relay N, and wire 44 back to battery Q².

The circuit for causing signal S⁷ to indicate proceed is now closed and passes from a battery Q³, through wire 59, contacts 60 and 61^a of relay H⁷, wire 62, operating mechanism of signal S⁷, and wire 64 back to battery Q³. The proceed indication control circuit for signal S⁵ is similarly controlled by contacts 54 and 55^a of relay H⁵.

I will now assume that, with all parts thus in their normal condition, a westbound train enters section C—D, de-energizing relay G³ which then opens the circuit for relay H⁵,

causing signal S⁷ to indicate "stop". As the train proceeds further and enters section B—C, relay G² becomes de-energized, opening the circuit previously traced for relay H⁵ and the primary winding 23 of transformer M. Relay H⁵, upon becoming de-energized, opens its contact 34 in the circuit already traced for relay N, which, on account of the de-energization of transformer M, is already de-energized and opens its front contacts and 75 closes its back contacts 38^b and 43^b.

As the train leaves section C—D, relay H⁷ becomes energized in its reverse direction by current flowing from battery Q², through wire 37, contact 43^b of relay N, wire 42, winding of relay H⁷, wire 41, contact 40 of relay G³, wire 39, contact 38^b of relay N, and wire 44 back to battery Q². With relay H⁷ energized in its reverse direction, signal S⁷ is now operated to its caution position by its circuit passing from battery Q³, through wire 59, contacts 60 and 61^b of relay H⁷, wire 63, operating mechanism of signal S⁷, and wire 64 back to battery Q³.

As the train later starts into section A—B, relay G¹ closes its back contact 67, thus completing for a brief period, while contact 65 of relay P continues closed, a pick-up circuit for relay T passing from battery Q¹, through wires 5, 10 and 45, contact 65 of relay P, wire 66, contact 67 of relay G¹, wire 68, winding of relay T, and wires 69 and 9 back to battery Q¹. Relay G¹ upon becoming de-energized, opens, at its contact 4, the circuit for relay H³, and hence relay T, upon becoming energized, completes its own stick circuit passing from battery Q¹, through wires 5 and 6, contact 70 of relay H³, wire 71, contact 72 of relay T, wire 73, winding of relay T, and wires 69 and 9 back to battery Q¹. After a sufficient interval of time has elapsed, slow release relay P opens its contact 65, thus breaking the pick-up circuit for relay T which, however, continues energized by its stick circuit, as already traced, while the train is proceeding through section A—B.

When the train leaves section B—C, relay H⁵ becomes energized in its reverse direction by current flowing from battery Q¹, through wires 5, 10 and 45, contact 27^b of relay P, wires 26, 25 and 21, winding of relay H⁵, impedance unit 20, wire 19, contact 18 of relay G², wire 17, impedance unit 16, wire 15, contact 14 of relay T, wire 13, contact 11^b of relay P, and wire 9 back to battery Q¹. At the same time, alternating current is supplied to primary winding 23 of transformer M by a circuit passing from source X, through wire α , contact 79 of relay T, wire 80, resistance unit 76, wire 17, and thence by the circuit previously traced for primary winding 23 to wire 25, and from there through wire 82, contact 81 of relay T, and wire α back to source X. With relay H⁵ now energized in its reverse direction, the arm of signal S⁵ is oper- 130

ated to the caution position by its circuit passing from battery Q^2 , through wire 53, contacts 54 and 55^b of relay H^5 , wire 57, operating mechanism of signal S^5 , and wire 58 back to battery Q^2 . On account of transformer M being supplied with alternating current and contact 34 of relay H^5 being closed, relay N is energized, and hence relay H^7 is again energized in its normal direction, 5 causing the arm of signal S^7 to be returned to its "proceed" position.

When the train leaves section A—B, permitting relay G^1 to again become energized, and assuming that signal relay H^3 now becomes energized in its reverse direction causing relay P to again become energized, current of normal polarity will again be supplied to relay H^3 by the circuit previously traced, thus causing signal S^5 to again display the proceed indication. With relay H^3 energized in the reverse direction, the arm of signal S^3 is operated to the caution position by a circuit passing from battery Q^1 , through wires 5, 10, 45 and 46, contact 47 of relay P , 20 wire 48, contact 49^b of relay H^3 , wire 51, operating mechanism of signal S^3 , and wire 52 back to battery Q^1 .

When relay H^3 again becomes energized in its normal direction after the train has passed 30 a sufficient distance beyond signal S^3 , the proceed indication will again be displayed by signal S^3 as already described.

I will now assume that with all parts again in their normal condition, an eastbound train 35 de-energizes relay H^3 , causing signal S^3 to indicate stop and relay P to become de-energized. With relay P de-energized, and with relays G^1 and G^2 energized, current of reverse polarity is now supplied to relay H^5 by the circuit previously traced, except including contact 12 of relay G^1 instead of the branch path through contact 14 of relay T . The circuit for primary winding 23 of transformer M is, however, open. With relay H^5 40 energized in its reverse direction, signal S^5 will indicate caution, and with relay N de-energized on account of primary winding 23 of transformer M being de-energized, relay H^7 will be supplied with current of reverse polarity, and hence signal S^7 , as well as signal S^5 , will indicate caution.

When the train enters section A—B, relay G^1 becomes de-energized, opening the circuit for relay H^5 , and thereby causing the 55 arm of signal S^5 to be operated to its stop position while the arm of signal S^7 continues to indicate caution. The arm of signal S^7 will remain in this position until the train de-energizes relay G^3 .

From the foregoing description and the accompanying drawing, it is clear that the arm of signal S^5 is operated to the caution position as soon as a westbound train leaves section B—C but that it is operated to the 60 stop position as soon as an eastbound train

enters section A—B, and thus the caution indication of signal S^5 is controlled through section B—C only, for following train movements, but is provided with overlap control through section A—B, for opposing train 70 movements, whereas, in common forms of absolute permissive block signaling, overlap control of the caution indication of signals S^4 and S^5 is provided for both following and opposing train movements. 75

From the foregoing description and the accompanying drawing, it is also clear that the proceed indication of signal S^7 is interrupted when an eastbound train de-energizes relay H^3 but that with a westbound traffic 80 movement signal S^7 displays its proceed indication as soon as the train leaves section B—C.

Although I have herein shown and described only one form of railway signaling 85 apparatus embodying my invention, it is understood that various changes and modifications may be made therein within the scope of the appended claims without departing from the spirit and scope of my invention. 90

Having thus described my invention, what I claim is:

1. In combination, a stretch of railway track comprising a first and a second section, a first signal, a second signal, a control circuit for said first signal controlled by traffic conditions in said first section and energized by current from a direct current source, and a control circuit for said second signal including the wires of said first signal control circuit and controlled by traffic conditions in said second section and energized by current from an alternating current source. 95

2. In combination, a stretch of railway track comprising a first and a second section, a first signal, a second signal, a control circuit for said first signal controlled by traffic conditions in said first section and energized by current of a given character, and a control circuit for said second signal including the wires of said first signal control circuit and controlled by traffic conditions in said second section and energized by current differing in character from the current by which said first signal control circuit is energized. 105

3. In combination with a railway home signal, a distant signal for said home signal, a control circuit for said home signal energized by current of a given character, and a control circuit for said distant signal including the wires of said home signal control circuit and energized by current differing in character from said home signal control current and energized only while said home signal control circuit is energized. 110

4. In combination, a stretch of railway track comprising a first and a second section, a first signal, a second signal, a pair of conductors, and means including current of a given character and current of a different 130

character supplied to said conductors for selectively controlling said first and second signals according to traffic conditions in said first and second sections, respectively.

5. In a railway signaling system, a passing siding connected with a stretch of main railway track, a permissive signal for governing the movement of traffic in a given direction through that portion of said stretch with 70
10 which said siding is connected, an absolute signal for governing the movement of traffic in said given direction away from that portion of said stretch with which said siding is connected, means for causing said permissive signal to indicate stop when traffic moving in said given direction occupies that portion of said stretch which is between said permissive and absolute signals only, and means for causing said permissive signal to indicate 75
15 stop when traffic moving in the opposite direction occupies a portion of said stretch in advance of said absolute signal as well as when traffic moving in said opposite direction occupies that portion of said stretch which is 80
20 between said permissive and absolute signals. 25

6. In a railway signaling system, two adjoining sections of railway track, a track circuit for each of said sections each including a track relay, a first and a second and a third 85
30 signal, a control relay controlled in part by a front contact of the first of said track relays, a slow release relay controlled by a front contact of said control relay, a stick relay, a pick-up circuit for said stick relay controlled by a front 90
35 contact of said slow release relay and by a back contact of said first track relay, a stick circuit for said stick relay controlled by a back contact of said control relay, means for controlling said first signal by said control relay 95
40 and by said slow release relay, a first and a second conductor, a second control relay responsive to direct current and connected across said conductors through an impedance unit having high impedance to alternating current but low resistance to direct current, a direct current source connected across said 100
45 conductors through a front contact of each of said first and second track relays and through pole-changing contacts of said slow release relay and through a second impedance unit similar to said first impedance unit, a branch path around said front contact of said first track relay passing through a front contact of said stick relay, an alternating 105
50 current source connected across said conductors through a resistance unit and through a front contact of said slow release relay and of said second track relay, a branch path 110
55 through a front contact of said stick relay passing around said slow release relay contact in series with said alternating current source, a third control relay energized when current from said alternating current source 115
60 is supplied to said conductors while said second control relay is energized, means for 120
65 controlling said second signal by said second control relay, a fourth control relay responsive to the polarity of the current supplied to its winding, a control circuit for said fourth control relay supplied with current of normal or reverse polarity according as 125
70 said third control relay is energized or de-energized, and means for controlling said third signal by said fourth control relay. 75

7. In combination, a first and a second section of railway track, a first and a second signal, a pair of conductors, a source of current, a second source of current of different character from the current from said first source, a control means responsive to current 80
80 from said first source, a second control means responsive to current from said second source, means for supplying current from said first source to said conductors according to traffic conditions in said first section, means for supplying current from said second source to 85
85 said conductors according to traffic conditions in said second section, means including said conductors for supplying said first control means with current from said first source, 90
90 means including said conductors for supplying said second control means with current from said second source, means for controlling said first signal by said first control means, and means for controlling said second signal by said second control means. 95

8. In combination, a first and a second section of railway track, a first and a second signal, a pair of conductors, a source of current, a second source of current of different 100
100 character from the current from said first source, a control means responsive to current from said first source, a second control means responsive to current from said second source but not to current from said first source, 105
105 means for supplying current from said first source to said conductors according to traffic conditions in said first section, means for supplying current from said second source to said conductors according to traffic conditions 110
110 in said second section, means including said conductors for supplying said first control means with current from said first source, means including said conductors for supplying said second control means with current 115
115 from said second source, means for controlling said first signal by said first control means, and means for controlling said second signal by said second control means. 120

9. In combination, a first and a second section of railway track, a first and a second signal, a pair of conductors, a source of current, a second source of current of different character from the current from said first source, a control means responsive to current 125
125 from said first source, a second control means responsive to current from said second source, means for supplying current from said first source to said conductors according to traffic conditions in said first section, means for sup- 130
130

plying current from said second source to said conductors according to traffic conditions in said second section, means including said conductors for supplying said first control means with current from said first source, means including said conductors for supplying said second control means with current from said second source, means for preventing current from said first source from reaching said second control means, means for controlling said first signal by said first control means, and means for controlling said second signal by said second control means.

10. In combination, a first and a second section of railway track, a first and a second signal, a pair of conductors, a source of direct current, a source of alternating current, a control means responsive to direct current, a control means responsive to alternating current, means for supplying current from said first source to said conductors according to traffic conditions in said first section, means for supplying current from said second source to said conductors according to traffic conditions in said second section, an impedance unit for obstructing the flow of alternating current, a resistance unit, means including said conductors for supplying said first control means with current from said first source through said impedance unit, means including said conductors for supplying said second control means with current from said second source through said resistance unit, means for controlling said first signal by said first control means, and means for controlling said second signal by said second control means.

In testimony whereof I affix my signature.
CHARLES W. BELL.
